* cited by examiner

Primary Examiner—Robert M. Spear*Assistant Examiner*—George D Kirschbaum(74) *Attorney, Agent, or Firm*—Bell, Boyd & Lloyd LLP(57) **CLAIM**

I claim the ornamental design for foldable stand for cross-cut saws, as shown and described.

DESCRIPTION

FIG. 1 is a perspective view of a foldable stand for cross-cut saws showing my new design;

FIG. 2 is a top view thereof;

FIG. 3 is a left side view thereof;

FIG. 4 is a right side view thereof;

FIG. 5 is a rear view thereof;

FIG. 6 is a bottom view thereof; and,

FIG. 7 is a front view thereof.
